UNITED STATES PATENT OFFICE.

CHARLES E. BABCOCK, SR., OF YORK, PENNSYLVANIA.

DESIGN FOR A BADGE OR SIMILAR ARTICLE.

51,569.

Specification for Design.

Patented Dec. 18, 1917.

Application filed September 1, 1917. Serial No. 189,415. Term of patent 3½ years.

To all whom it may concern:

Be it known that I, CHARLES E. BABCOCK, Sr., a citizen of the United States, residing at York, in the county of York and State of Pennsylvania, have invented a new, original, and ornamental Design for a Badge or Similar Article, of which the following is a specification, reference being had to the accompanying drawing, forming part thereof.

The figure is a face view of a badge, illustrating my new design.

I claim:

The ornamental design for a badge or similar article, as shown.

CHARLES E. BABCOCK, Sr.

In presence of—

SAMUEL KURTZ,

ROBERT KING.
